UNITED STATES PATENT OFFICE.

CHARLES VALLONE, OF BUFFALO, NEW YORK, ASSIGNOR TO BARCALO MANUFACTURING COMPANY, OF BUFFALO, NEW YORK.

SPRING-BOTTOM FOR BEDS AND THE LIKE.

1,261,655.

Specification of Letters Patent.

Patented Apr. 2, 1918.

Application filed June 18, 1914. Serial No. 845,828.

To all whom it may concern:

Be it known that I, CHARLES VALLONE, a citizen of the United States, residing at Buffalo, in the county of Erie and State of New York, have invented a new and useful Improvement in Spring-Bottoms for Beds and the like, of which the following is a specification.

This invention relates to that type of bed springs or spring bottoms for beds, couches or other furniture, which are composed of a number of upright spiral or coil springs secured on a supporting frame or structure. It is usual in these bottoms to provide tie means of some sort for connecting the upper ends of the springs to retain them upright in the intended relative arrangement and equalize the strains due to a weight on the bottom, and this invention is directed 20 to improvements in such tie means or devices.

The objects of the invention are to provide tie means for the spiral springs which will effectually retain the springs in the intended relative arrangement, and at the same time insure a very pliant and comfortable spring bottom which will readily conform to the body of a person resting on the bottom; also to make the tie means of the minimum number of parts of simple construction which can be readily applied to the bottom at small expense and which will leave the upper surface of the bottom free from projections that are apt to catch in or injure 35 the covering of the mattress.

In the accompanying drawings:

Figure 1 is a plan view of a portion of a bed bottom embodying the invention.

Fig. 2 is a plan view, on an enlarged scale, 40 of a section of the bottom.

Fig. 3 is a sectional elevation thereof in line 3—3, Fig. 2.

Fig. 4 is a sectional elevation thereof, full size, in line 4—4, Fig. 2.

Fig. 5 is a sectional elevation thereof, full size, in line 5—5, Fig. 2.

Fig. 6 is a sectional elevation thereof, on a reduced scale in line 6—6, Fig. 5.

Fig. 7 is a sectional elevation in line 7—7, 50 Fig. 4.

Fig. 8 is an elevation of one of the securing clips before it is applied to the bed bottom.

Fig. 9 is a fragmentary plan view of a bed

bottom provided with tie means of slightly modified construction.

A represents the upright spiral or coil springs, which are secured on a supporting frame or structure B. This frame and the springs A may be of any known or suitable form and construction, and the springs may be secured on the frame in any suitable way. C represents the usual upper marginal rectangular frame or rod surrounding the upper ends of the springs and to which they are connected by the tie devices about to be described.

The springs A are arranged in parallel rows running both lengthwise and crosswise of the bottom.

D represents tie bands, one of which extends between and is connected to the springs in two adjacent parallel rows running one way of the bottom, for instance the rows running lengthwise. Each band is fastened to the springs in the two rows extending lengthwise at opposite sides thereof in a way, such as hereinabove described, that the springs are held from displacement both lengthwise and crosswise relative to the tie band, so that by fastening the ends of the tie bands to the upper frame C and connecting the ends of the rows of springs which run in the other direction, that is, crosswise of the bottom in the construction shown, all of the springs are retained in place without the necessity for tie strips or wires extending crosswise of the bed bottom or at right angles to the tie bands D. The ends of the tie bands D can be bent around the frame C or fastened thereto in any other convenient way.

The tie bands D consist of bands or strips of metal which are thin and therefore very flexible, adapting them to yield or give vertically under a very light pressure. Each tie band D is provided at intervals with transverse bends or depressions E, preferably V-shaped, provided with slots e which intersect the same and preferably extend lengthwise of the band from end to end of the bends E, these bends or depressions E being spaced apart a distance equal to the distance from center to center of the transverse rows of springs. Each tie band D lies flat upon the top coils of the adjacent portions of the springs in the parallel rows of springs at opposite sides of the tie band,

and the top coils of the two springs adjacent to each bend or depression E pass through or are seated in the slot e in said bend. The springs may be fastened in the 5 slots e by separate clips or securing devices F for each pair of springs, as shown in Figs. 1-8, or the several springs in each transverse row may be fastened to the tie bands, as shown in Fig. 9, by a single continuous wire 10 G extending from side to side of the spring bottom.

The separate clips F, see Fig. 8, preferably consist of short pieces of wire one end of which is bent to form a hook f. The straight 15 end of this wire clip is slipped in between the bottom of the bend or depression of the tie band E and the coils of the springs seated in the slot e in said bend until the clip is arrested by the engagement of the hook f 20 with one edge of the tie band. The straight end of the clip wire is then bent downwardly over the other edge of the tie band, as shown in Fig. 7, thereby securing the clip on the tie band. The tie bands can be fastened to the springs very rapidly and with little trouble by the clips F. When separate clips are thus used for fastening the tie bands to the springs, the springs at the 25 ends of the transverse rows are connected to the upper frame C by extensions H of the clips used for the end springs, or by any other suitable connections.

When the continuous securing wires G, shown in Fig. 9, are used they are passed 30 through the bends or depressions E of the tie bands beneath the top coils of the springs and their ends are bent around or otherwise fastened to the sides of the top frame C. The continuous securing wires G enable the 35 tie bands to be fastened to the springs more expeditiously and they prevent movement of the springs relative to the tie bands D in the same way as the separate clips F, but the use of the separate clips has the advantage that the spring bottom is thereby made 40 more pliant, as will be more readily apparent from an examination of Figs. 5 and 6. If, for example, one of the tie bands is depressed, as indicated in Fig. 5, by a weight 45 disposed locally over one of its connections with the springs, the adjacent springs are free to rock in the slot e in which they are seated and assume a tilted or inclined position, as shown in Fig. 6. The bottom with 50 the separate securing clips F will yield or give in this way under less weight than a bottom having the continuous securing wires, since, when the latter are used, it is necessary to flex them in addition to the tie 55 bands.

In both of the constructions described, each of the tie bands D is directly connected to the springs in the two parallel rows at opposite sides thereof by inter-engaging 60 parts of the tie bands and springs without

additional parts other than the plain securing wires or wire clips, which hold the inter-engaging parts in connection. The tie means are therefore composed of the fewest possible parts which are of exceedingly simple construction and can be made and applied to the bed bottom at small expense. The described tie means insure an exceptionally easy or comfortable spring bottom, for the tie bands D are made of very thin metal 70 and are more flexible than tie wires of sufficiently large gage to give the necessary strength. The thin flat tie bands lie flat upon the tops of the springs and the connecting or securing parts are all located below the plane of the bands, so that the bottom has a smooth flat mattress-supporting 75 surface free from upward projections. Tie bands constructed just as described could also, if desired, be secured, in the manner 80 described, to the springs in one row only, instead of each tie band being secured to two rows of springs.

It will be manifest that the tie bands could be inverted and arranged beneath the 85 top coils of the springs and connected thereto in the manner described, but this arrangement would be less desirable as the bends E would form upward projections on the mattress-supporting surface. In some spring 90 bottoms, double springs are used which are secured between their ends to the supporting frame and extend above and below the same, both the top and bottom ends of the 95 springs being connected by tie devices. The 100 tie means of this invention are of course equally applicable to this double or reversible type of spring bottoms.

I claim as my invention:

1. A spring bottom for beds and the like, 105 comprising a supporting frame, upright springs secured thereon in rows, thin flat tie-bands each arranged lengthwise between two rows of springs running one way of the bottom and having slotted bends in the slots of 110 which the end portions of the springs in said two rows are seated, and means for securing the springs in said slotted bends.

2. A spring bottom for beds and the like, 115 comprising a supporting frame, upright coil springs secured thereon in rows, thin flat tie-bands which extend lengthwise of the rows of springs and have slotted bends, the end coils of two of said springs being seated in each of said slotted bends, and means for 120 securing the springs in said slotted bends.

3. A spring bottom for beds and the like, 125 comprising a supporting frame, upright springs secured thereon in rows, thin flat flexible tie-bands arranged lengthwise of the rows of springs running one way of the bottom and having slotted bends in which the upper end portions of the springs are seated, means for securing the springs in said slotted bends, said tie-bands connecting 130

the rows of springs running both lengthwise and crosswise of the bottom, a marginal frame to which said tie-bands are secured at their ends, and means for connecting the rows 5 of springs running crosswise relative to said tie-bands to said marginal frame.

4. A spring bottom for beds and the like, comprising a supporting frame, upright springs secured thereon in rows, thin flat tie-bands arranged lengthwise of the rows 10 of springs running one way of the bottom and having slotted bends in which the end portions of the springs are seated, separate means for each tie-band for securing the

same to said springs, each tie-band being 15 secured to the springs in two adjacent rows running parallel with the tie-band, a marginal frame to which said tie-bands are secured at their ends, and means for connecting the rows of springs running crosswise 20 relative to said tie-bands to said marginal frame.

Witness my hand, this 15th day of June, 1914.

CHARLES VALLONE
